(57) CLAIM

The ornamental design for a lingerie hanger, as shown and described.

DESCRIPTION

Portions of the disclosure of this patent document contain material that is subject to copyright protection. The copyright owner has no objection to the facsimile reproduction by anyone of the patent document or the patent disclosure as it appears in the Patent and Trademark Office file or records, but otherwise reserves all copyright rights whatsoever.

FIG. 1 is an exploded perspective view of a lingerie hanging device showing my new design;

FIG. 1 is a first side view thereof;

FIG. 2 is a second side view thereof;

FIG. 3 is a third side view thereof;

FIG. 4 is a fourth side view thereof;

FIG. 5 is a fifth side view thereof;

FIG. 6 is a top view thereof; and,

FIG. 7 is a bottom view thereof.

The broken lines shown in the drawing disclosure are for illustrative purposes only and form no part of the claimed design.
